EXPANSION JOINT

Walter Kasten, Franklin, Mich., assignor to Ren-
niks Company, Detroit, Mich., a copartnership

Application May 15, 1946, Serial No. 669,965

6 Claims. (Cl. 285—162)

1

The present invention pertains to certain valuable novel structural betterments and functional refinements in expansion-joints or couplings for conduits or pipes, such as those used for conveying high-pressure, high-temperature steam or comparable fluids, although its employment is not necessarily limited to such specific utilization.

Among the several objects and purposes of this recent invention may be mentioned the provision of (a) an expansion-joint which avoids the commonplace loop in the pipe thus supplying a structure occupying relatively small space, (b) one which consists of comparatively few parts, (c) one which may be constructed at relatively small cost, (d) one which effectively and efficiently performs its function of allowing expansion and contraction of the conduit without leakage or breakage, (e) one which will have substantially no tendency to get out of order, and (f) one which will be without likelihood to become damaged or injured while performing its ordinarily satisfactory service.

To enable those acquainted with and skilled in this art to readily understand the structural improvements and functional advantages incident to the new invention, a present preferred material embodiment of the same has been illustrated in the accompanying drawing forming a part of this specification and to which reference should be had in connection with the following detailed description, like reference numerals having been employed to designate the same parts of the structure in the views of the drawing.

In this drawing:

Figure 1 is an external view of the novel and improved pipe-joint; and

Figure 2 is a central longitudinal section through the joint on line 2—2 of Figure 1 on a larger scale.

By reference to this drawing, it will be noted that each of the two, companion, opposed pipe-sections 10 and 11 to be connected together by the novel expansion-and-contraction joint is supplied with an apertured terminal flange 12, secured by bolts 13, 13 to the correspondingly-apertured end-flanges 14 and 15 of a pair of hollow, interfitted, cylindrical conduit-members 16 and 17, a suitable flat pressure-sealing gasket 18 being employed between each pair of flanges 12 and 14 and, if desired in some cases, although it is not always required, a similar or comparable gasket may be used between the flanges 14 and 15, although not so illustrated.

It should be observed that an appropriate, expansion-and-contraction space or gap 19 is provided between the adjacent ends of the reversely-arranged, companion elements 17, 17.

The channel or passage through each round member 16 in register with that of the adjoining pipe-section 10 or 11, is enlarged at its inner end, as shown at 21, to loosely accommodate a termi-

nal portion of a tubular-element 22 having a medial, external, round flange 23 partially only as wide as, and occupying, the gap 19 to allow play between the adjacent members of the joint, the passages through all five parts 10, 11, 16, 16 and 22 being in register and ordinarily, but not necessarily, approximately of the same caliber.

As is clearly illustrated, the inner end of each member 17 has an internal, circular, terminal bead, flange or shoulder 24 with a round, inwardly-converging surface 25 merging into a larger-diameter face 26 at a right-angle to the axis of the joint.

Bearing and resting on and conforming to each of these combined surfaces or shoulders 25, 26 is a circular gasket or pressure-seal 27 composed preferably, but not necessarily exclusively, of a plurality of interfitted or nested, thin, resilient or elastic, truncated-cone, sheet-metal reeds with their inner circular edges disposed inwardly beyond the inner-surface of the member 24, in pressure-sealing engagement with and completely surrounding the external, cylindrical surface of the intermediate tube 22, the two seals 27, 27 facing in opposite directions, that is, toward the fluid-pressures to which their opposite outer surfaces are subjected by reason of the tortuous spaces 21, 31.

Stated somewhat otherwise, and as shown in the drawing, the outer surface of tube 22 is slightly less in diameter than the inner-diameter of the shoulders 24, 24 so that the inner marginal portions of the reeds 27 project slightly beyond the former into engagement with the tube and, as mentioned, there is also an annular space 31 between each end portion of the tube 22 and the adjacent inner-surface of the corresponding member 16 so that the fluid-pressure in the joint is applied directly to both reed-seals tending to keep them tight and in proper functioning capacity.

As is fully depicted, the external-diameter of each hollow cylindrical member 16 is approximately the same as the internal-diameter of its complementary housing member 17 in which it fits and the circular end of each member 16 is made thin to bear only on the outer part of the corresponding reed-seal 27 and to press the same firmly against and tightly on the companion surface 26 of the shoulder 24, the parts being maintained in such relation by the holding bolts 13.

Obviously, as the sections of pipes 10 and 11 and others joined thereto, but not illustrated, expand and contract under temperature changes, the novel joint illustrated and described readily compensates for such elongations and shortenings without pressure-leakage due to the fact that such length changes of the conduit as a whole cause the reed-seals to ride back and forth on the tube 22 without pressure loss and the tube itself is also capable of a moderate amount of

lengthwise play by reason of the spaces between the flange 23 and the adjacent ends of the elements 17, 17 and the spaces at the ends of the tube.

It will be observed that the expansion-and-contraction referred to is permitted because of the gap 19 between the parts 17, 17 and that the reed-seals are able to maintain their pressure-tight relations because their outer surfaces are always subjected to the fluid-pressure in the pipe-sections 10 and 11.

In addition to the novel structural features already described, the adjacent ends of the two members 17, 17 are desirably provided externally with heat-dissipating flanges 32, 32 which, together with the neighboring or intervening heat-dispersion flange 23 of tube 22, adequately protect the structure from heat damage.

Moreover, in order to prevent the structure from cocking or becoming distorted during movement of the parts caused by the heating or cooling of the pipe, all of the nine flanges 12, 14, 15, 32 and 23 are apertured in register at a plurality of points, three or more, each such longitudinal group housing a guide-rod 33 of substantially the same diameter with terminal enlarged limit-stops 34 and 35 spaced apart the proper amount to prevent disengagement of the reeds due to excessive extension of the pipe-ends, these rods also providing additional cooling surface and hence aiding in reducing the operating temperature of the metallic sealing-reeds.

Those skilled in and acquainted with this art will readily understand that the present invention is not indispensably limited and confined to the precise and exact features of construction and mode of operation herein set forth and that reasonable modifications may be availed of without departure from the heart and essence of the invention and without the loss or sacrifice of any of its material benefits and advantages.

I claim:

1. In an expansion-and-contraction joint adapted to be secured between and to terminal flanges of spaced-apart ends of a pair of aligned pipe-sections, the novel combination of an intermediate externally-cylindrical tube, a pair of longitudinally spaced-apart conduits each including an outer tubular-member and a complementary inner tubular-member lengthwise slidingly accommodated in said outer tubular member, each said tubular member having an external terminal flange, means to adjust said flanges longitudinally relative to one another, each said inner tubular member housing its corresponding end portion of said tube with a space between and around the two and with lengthwise play between the two, each said outer tubular member having an internal annular shoulder in register with the end of its corresponding inner tubular member and a thin, flexible, truncated-cone reed-gasket between each said shoulder and the end of the corresponding inner tubular member bearing edgewise in slidable engagement with said tube, said two reed-gaskets sloping in opposite directions and adapted to be subjected to the fluid-pressure in the joint.

2. In an expansion-and-contraction pipe-joint between pipe-sections having terminal flanges, the combination of a pair of conduits each having an inner externally-flanged element and an outer, double, externally-flanged element, a tubular member inside of said conduits, thin elastic read-type pressure-seals mounted on said conduits and bearing edgewise on the external-

surface of said tubular-member, and guide-rods with limit-stops occupying registered apertures in all of said flanges.

3. In an expansion - and - contraction joint adapted to be secured between and to the spaced-apart ends of a pair of aligned pipe-sections, the novel improvement of an externally round tube, a pair of longitudinally spaced-apart conduits adapted to be fastened to the ends of said pipe-sections and form extensions of the latter and each housing the corresponding end portion of said tube, and a gasket inside each said conduit and surrounding its encased portion of the tube and in fluid-pressure sealing engagement with the conduit and in fluid-pressure sealing sliding engagement with the exterior of its portion of the tube, each said conduit consisting of an inner tubular member encased in a complementary outer tubular member, the gasket being maintained fixedly in place between portions of said complementary tubular members.

4. In an expansion - and - contraction joint adapted to be secured between and to the spaced-apart ends of a pair of aligned pipe-sections, the novel improvement of an externally round tube, a pair of separate longitudinally spaced-apart externally flanged conduits adapted to be fastened by their flanges to the ends of said pipe-sections and each conduit internally housing its corresponding end portion of said tube with lengthwise play therewith, and a gasket for each said conduit and surrounding its encased portion of said tube and in fluid-pressure sealing engagement with both said conduit and said tube and in sliding engagement with at least one of the two, said gasket being of the thin, annular, elastic, metal reed-type.

5. The novel improvement set forth in claim 4, in which each said gasket is fixed to its conduit and is in sliding engagement with the exterior of the tube.

6. In an expansion - and - contraction joint adapted to be secured between and to the spaced-apart ends of a pair of aligned pipe-sections, the novel improvement of an externally round tube, a pair of separate longitudinally spaced-apart externally flanged conduits adapted to be fastened by their flanges to the ends of said pipe-sections and each conduit internally housing its corresponding end portion of said tube with lengthwise play therewith, and a gasket mounted on each said conduit and surrounding its encased portion of said tube and in fluid-pressure sealing relation with both said conduit and said tube and in sliding engagement with the exterior of the tube, each said gasket being of the annular, thin, elastic, metal reed-type with the two gaskets facing in opposite directions.

WALTER KASTEN.
